CLAIM

The ornamental design for a wood burning stove with screen, as shown.

DESCRIPTION

FIG. 1 is a perspective view of a wood burning stove with screen, showing our new design;

FIG. 2 is a left side elevational view thereof;

FIG. 3 is a plan view thereof;

FIG. 4 is a right side elevational view thereof;

FIG. 5 is a front elevational view thereof; and

FIG. 6 is a rear elevational view thereof.
